TILTABLE TOY

Hermann Neuhierl, 36 Waldestrasse,
8510 Furth, Bavaria, Germany

Filed Oct. 29, 1971, Ser. No. 194,102

Claims priority, application Germany July 5, 1971

Term of patent 14 years

Int. Cl. D21—01

U.S. Cl. D34—15 A

FIG. 3

FIG. 4

FIG. 1 is an elevational view of the tiltable toy showing my new ornamental design.

FIG. 2 is an elevational view of the toy in a tilted position with the removable elements detached therefrom;

FIG. 3 is a top plan view of the toy of FIG. 1; and FIG. 4 is a bottom plan view thereof.

FIG. 41
I. *Salvinia*

I claim:
The ornamental design for a tiltable toy, as shown and described.
